THERMALLY RESPONSIVE SWITCH

Charles Grimshaw, Fulton, Ill., assignor to General Electric Company, a corporation of New York

Filed Dec. 28, 1960, Ser. No. 78,923

12 Claims. (Cl. 200—137)

This invention relates to thermally responsive switches, and more particularly, thermally operated switches of the type having a housing or frame which constitutes a thermally responsive actuating element of the switch.

Thermally operated switches having a thermally responsive housing or frame are frequently used to provide thermal protection for electrical apparatus, such as electric motors. One prior art form of such a switch incorporates a tubular member which is expansible and contractible pursuant to predetermined variations in ambient temperature and also serves as a housing for the switch mechanism. Within the tubular member of this switch there is disposed another element which is also thermally expansible and contractible but at a slower rate. The tubular member and the interior element are arranged in the switch in such a manner as to control a contact means, with compensation for the rate at which the ambient temperature rises. For example, when there is a relatively rapid rise in ambient temperature, the tubular member insulates the interior element from the temperature change, and expands longitudinally to actuate the contact means at one temperature value. When a gradual or slower rise in ambient temperature is sensed by the switch, the interior element receives the effect of the heat and expands longitudinally to compensate for the expansion of the tubular member. The contacts are then actuated at a higher temperature value than the first value due to the compensating effect of the interior element. Such a mode of operation in thermally responsive switches of the prior art has been commonly referred to as "thermal anticipation."

To amplify the thermally responsive motions of the tubular member and the interior element in such prior art switches and to actuate the contact means thereof, various structural arrangements have been employed. These arrangements have proven to be complicated and relatively expensive. In addition, the structural configuration and arrangement of the various parts of some of these switches have necessitated an over-all switch structure which is relatively bulky and difficult to install in an associated apparatus. It has, therefore, been found desirable to provide an improved thermally responsive switch of the nature described, which is extremely efficient, simple, small in size, and readily manufacturable.

It is sometimes desirable to use these switches in the same environment as hermetically sealed apparatus, such as hermetic motors. For example, the hermetic motor might be part of a hermetically sealed compressor system. In this type of environment, it has been found that extraneous fluids such as oils and gases, as well as extraneous particles, often produce an adverse effect upon the longevity of the switch. It has, therefore, also been found desirable to provide a thermally responsive switch which is easy to hermetically seal and thereby efficiently lends itself to the association with and control of hermetically sealed apparatus.

Accordingly, it is the primary object of this invention to provide an improved thermally responsive switch which is novel in construction and very efficient in operation.

An additional object of my invention is to provide an improved thermally responsive switch which provides precise and consistent actuation of the contacts throughout the life of the switch.

Another object of this invention is to provide an improved thermally responsive switch that is hermetically

2

sealed, relatively small in size, sturdily constructed, and has a long life.

It is a further object of my invention to provide an improved thermally responsive switch which is hermetically sealed, and which due to its relative simplicity may be manufactured at a reduced cost.

Another object of my invention is to provide an improved thermally responsive switch having a built-in means for compensating the switch in accordance with the rate of ambient temperature change, and very accurate, but yet inexpensive, and readily assembled means for utilizing the actuating forces from two thermally responsive members to actuate the switch contacts.

In carrying out my invention, in one form thereof, I provide a hermetically sealed thermally responsive switch wherein switch elements are housed within an elongated tubular member that is sealed at each of its ends. An elongated support is positioned longitudinally within the tubular member. The tubular member and the support are expansible and contractible in response to temperature variations with the rate of expansion and contraction of the support lagging that of the tubular member. A force transmission lever is also positioned within the tubular member and it is operable between first and second positions. An actuator is pivotally mounted on the support and continuously engaged by the lever to amplify the movement of the lever and control a pair of switch contacts. The actuator is continuously spring biased into engagement with the lever to urge the lever toward its first position. The lever includes a force receiving section disposed transversely near one end of the tubular member and near one end of the support. One side of the force receiving section engages the adjacent end of the tubular member at a first pivot, and the other side of the section engages the adjacent end of the support at a second pivot which is spaced transversely from the first pivot. The tubular member and the support are arranged to exert offset and oppositely directed thermally responsive compressive forces upon the lever at the first and second pivots respectively. These compressive forces tend to move the first and second pivots in opposite longitudinal directions and are normally of sufficient magnitude to retain the lever in the second position against the force exerted thereupon by the spring biased actuator. When the ambient temperature increases, the tubular member expands longitudinally to move the first pivot and diminish the compressive force exerted upon the lever by the tubular member. When the rate of rise in temperature allows sufficient ambient heat to be sensed by the support, the support also expands longitudinally. The expansion of the support moves the second pivot and thereby increases the compressive force exerted upon the lever by the support. This movement of the second pivot lags the movement of the first pivot but partially compensates therefor, to provide compensation in the switch for the rate of temperature rise. By transmitting the thermally responsive forces of the tubular member and the support to the lever through the pivots and amplifying resultant movements of the lever to operate the switch contacts through the pivoted and spring biased actuator, a very efficient switch with precise and consistent actuation of the switch contacts is thereby obtained.

Further aspects of my invention will become apparent hereinafter, and the specification concludes with claims particularly pointing out and distinctly claiming the subject matter which I regard as my invention. The invention, however, as to organization and method of operation, together with further objects and advantages thereof, may best be understood by reference to the following description when taken in conjunction with the accompanying drawings, in which:

FIG. 1 is a perspective view of an improved thermally

responsive switch embodying my invention, with a pair of leads connected to the switch terminals;

FIG. 2 is a sectional side view of the switch of FIG. 1, with the insulating sleeve removed and the contacts in their normally closed position;

FIG. 3 is a sectional view taken along the lines 3-3 as indicated in FIG. 2;

FIG. 4 is a sectional end view taken along the lines 4-4 as indicated in FIG. 2, with the switch contacts in their closed position;

FIG. 5 is a view similar to the view of FIG. 4, but showing the switch contacts in their open position;

FIG. 6 is an exploded view showing the structural details of the various elements of the switch of FIG. 2;

FIG. 7 is a fragmentary view of the switch of FIG. 2 showing the association between the actuator, the movable contact and the fixed contact, when the switch contacts are in the open position;

FIG. 8 is a perspective view of the force transmission lever of the switch of FIG. 2; and

FIG. 9 is a sectional side view of a switch embodying my invention in alternate form thereof.

Referring now to the drawings and more particularly to FIGS. 1-3, I have shown a thermally responsive switch 1 wherein my invention has been advantageously employed. To furnish a diminutive housing for the various components of this switch, which also efficiently serves as a thermally responsive element, I have provided the tubular casing 3. In the illustrated embodiment, the size of casing 3 approximates that of a cylindrical pencil having a length of less than two and one quarter inches. Contact terminal assembly 5 is welded to upper end 7 of the casing 3 and nut 9 is welded to the lower end 11 thereof (as viewed in FIG. 2) to provide a smooth and compact hermetically sealed housing for the various internal switch parts. To electrically insulate the housing and enable the switch to be readily inserted in the winding of an electric motor, as shown in FIG. 1, a sleeve 13 of suitable electric insulating material, such as Mylar, is formed around the housing. It will be understood that the sleeve 13 is thermally conductive and very thin and therefore has little resistance to the transfer of heat to the switch housing. In addition, sleeve 13 is preferably thermally shrinkable so that it may be shrunk around the tubular member 3 and nut 9 in contiguous relationship thereto. This contiguous relationship minimizes any resistance to transfer of heat to the tubular member 3.

Turning now to a further discussion of the housing which has been provided for my improved switch 1, casing 3 is preferably made from a metallic material having a relatively high coefficient of expansion, such as stainless steel or brass. Contact terminal assembly 5 includes a cylindrically-shaped terminal 15 which has an annular flange 17 formed at its inner end. End 7 of casing 3 is bent inwardly against the shoulder 16 of annular flange 17 and welded thereto to first close end 7 of the switch housing. Fixed contact terminal 19 extends axially through terminal 15, being separated therefrom and supported therein by fused electrical insulating material 21. Inner end 23 of the fixed contact terminal is flattened on opposite longitudinal sides (as shown in FIG. 2) to support fixed contact button 25 of the switch.

To close the other end 11 of casing 3, after contact terminal assembly 5 has been welded to casing 3, the various parts of the switch have been positioned within the housing, and the switch has been properly assembled, nut 9 is welded to the casing, preferably by spot welding. To hermetically seal the switch, the end 11 may be dipped in molten solder. As shown in FIG. 6, nut 9 includes a partially ring-shaped shoulder 26 which engages the major portion of end 11 of the casing 3. Nut 9 is partially cylindrical in configuration to seat against the inner wall of casing 3, but is truncated or reduced to provide a flat side 9a parallel to the axis of the nut. Flat side 9a of the nut allows flexible strip 27 to be extended outwardly from bot-

tom end 11 of the casing after the assembly of the various parts within the housing, for the adjustment of the temperature differential before end 11 is sealed. The structure and function of the flexible strip 27 shall be described in detail hereinafter. The nut 9 has a centrally disposed threaded aperture extending axially therethrough which is engaged by adjustment screw 29. This adjustment screw serves to calibrate the switch for proper response to the thermally responsive actuating forces, as shall hereinafter become apparent.

Turning now to a consideration of the interior of switch 1, as shown in FIGS. 2 and 3 (the separate parts being best seen in FIG. 6), an elongated support 35 is positioned longitudinally within switch cavity 37. This support 35 serves as a second thermally responsive element encased within the housing and is preferably constructed of steel. More particularly, support 35 resembles in overall appearance, a generally U-shaped channel, and, as shown in FIG. 6, includes elongated sides 38 which are spaced apart in parallel relationship by longitudinally spaced U-shaped bight sections or ribs 39, 41, 43, 45, and 47. Stepped upper ends 49 of the sides 38 compressively engage the inner surface of terminal 15 on opposite sides of the inner end of fixed contact terminal 19. (See FIGS. 2 and 3.) Rib 39 is formed at the other end of support 35. As shown in FIG. 6, rib 39 includes an extension which is curved slightly inwardly or in the direction of sides 38 and has a sharp transverse knife edge 51 formed thereon. The purpose of the knife edge 51 is to transmit thermally responsive force variations from within the switch housing to a motion amplifying lever assembly, as shall be described hereinafter.

For pivotally supporting a switch actuating means, connecting rib 41 is spaced longitudinally from end rib 39 by a slot 52. A pair of fingers 53 are spaced apart laterally and curved angularly inwardly from the inner surface of the upper end of rib 41 (FIG. 2). Fingers 53 extend angularly toward the left side of casing 3 and upwardly away from slot 52, as viewed in FIG. 2, having a space 54 therebetween (FIG. 6) and sharp outer edges which provide a pair of knife edge supports for switch actuator 55.

Switch actuator 55 resembles in general a U-shaped channel which is not as deep as support 35, as shown in FIG. 4. The structure of actuator 55, as best shown in FIG. 6, includes a pair of elongated sides 57 which are held together in parallel relationship by bight sections 65, 66, and 68. These bight sections are U-shaped and they are spaced apart longitudinally by the slots 59 and 61. Elongated bight section 65 extends between slot 59 and the bottom end 63 of the actuator. Section 65 has formed therein a centrally disposed lanced tab 67 and an adjacent stamped embossment 69. The free end of tab 67 extends angularly upwardly and to the right (viewing FIG. 2). Embossment 69 has the configuration of a D-shaped plateau on the right side thereof (FIG. 2). The bottom side of this plateau provides a pair of spaced apart transverse shoulders 71 (FIG. 6) which face toward end 63 of the actuator and are spaced slightly longitudinally upwardly from the free end of the tab 67 (FIG. 2). Shoulders 71 provide sharp inner edges which are transversely and linearly arranged.

Actuator 55 is positioned on the left side of the ribs of support 35 (viewing FIG. 2) with knife edges 53 of the support each linearly engaging beneath and against an associated one of the actuator shoulders 71. (See also FIG. 6.) The free end of lanced tab 67 projects angularly to the right, as shown in FIG. 2, and traverses between the knife edges 53 to laterally position the shoulders 71 upon their associated knife edges 53. The engagement of actuator shoulders 71 with knife edges 53 of the support thus provides an accurate pivotal support for the actuator with substantially minimal lateral movement of the actuator on its supporting pivots.

When actuator 55 is pivotally mounted upon support

35, L-shaped tab 72 of the support extends transversely to the left (FIG. 2) through slot 59 of the actuator and then upwardly, parallel to rib 43. The free end of tab 72 is thus positioned to the left of the bottom end of actuator bight section 66 to limit pivotal movement of the actuator in a counterclockwise direction of rotation.

To properly balance actuator 55 upon its pivots, a weight 73 of suitable magnitude is welded to the right side of bight section 65, as viewed in FIG. 2. In order to provide clearance for pivotal movement of the actuator 55 near bottom end 63 thereof, weight 73 lies generally within slot 52 of the support.

To operate the contacts of my improved switch 1, and thereby control an external circuit, the upper end of actuator 55 (as shown in FIG. 2) is specially formed to pivotally support and carry movable contact strip 75. (See also FIG. 6 and FIG. 7.) More particularly, bight section 68 of actuator 55 has an embossed spring seat 79 formed thereon which projects to the left, as shown in FIG. 2. An L-shaped extension 81 is formed on an upper prolongation of section 68. This extension 81 includes transverse portion 83 and a switch actuating arm 85 which extends longitudinally within cavity 37 on the left side of fixed contact button 25 (FIG. 2).

To efficiently guide and pivot movable contact strip 75 upon actuator 55, the strip 75 includes a channel-shaped section 87 and a channel-shaped contact extension 89. Strip 75 is preferably formed from a thin strip of silver metal. The longitudinal axes of section 87 and extension 89 of the strip are generally perpendicular to each other. Opposed sides 91 and 93 of extension 89 are parallel to each other and spaced apart to allow a suitable wipe distance for movement of the free end 95 of the actuator therebetween. The sides of channel section 87 serve to position the movable contact strip laterally relative to the actuator, as shown in FIG. 3.

Movable contact strip 75 is positioned upon the L-shaped extension of the actuator 55, as shown in FIGS. 2 and 7, with transverse portion 83 of the actuator extending through slot 94 of the contact strip. Free end 95 of arm 85 of the actuator is then disposed to the left of extension side 93 between it and side 91. Movable contact button 97 is embossed on the right side of contact extension 89 and disposed opposite to fixed contact button 25.

To normally bias movable contact button 97 toward fixed contact button 25 and provide a wiping action, as will be hereinafter explained, embossed spring seat 99 is formed in the bight portion of channel section 87. Seat 99 is positioned so as to face seat 79 of the actuator. (See FIG. 7.) Spring 101 runs in compression between the oppositely disposed seats 79 and 99 of the actuator and movable contact strip, respectively, to normally urge movable contact button 97 in a clockwise direction of rotation (viewing FIG. 7), the strip 75 pivoting at slot 94 around transverse actuator portion 83. When the switch contacts are closed, end 95 of actuator 55 is in engagement with side 93 of the movable contact strip 75. Spring 101 is then held in compression, as shown in FIG. 2, by the sandwiching of side 93 and the movable contact button 97 between actuator end 95 and rigid fixed contact 25.

In order to provide snap action for the switch contacts of switch 1, I have provided U-shaped toggle spring 103. This spring is in continuous compression between pivot edge 105 of flexible strip 27, and transverse projecting edge 107 which is formed on an upper extension of actuator bight section 66. Edges 105 and 107 of the actuator 55 and strip 27, respectively, engage indented end portions of the toggle spring 103, as shown in FIG. 7, to effect the snap action of the actuator about its pivots 71. Spring 103 pivots about strip edge 105 and continuously biases actuator 55 in the direction of the open position of the switch contacts, or with a counterclockwise moment of biasing force about pivoting shoulders 71 of the actuator.

To facilitate the adjustment of the biasing force applied to the switch actuator 55 by the toggle spring 103, after the various parts of my diminutive switch 1 are assembled within tube 3, the aforementioned flexible strip 27 is stretched in tension between the support rib 47 and the bottom end of the casing 3, as shown in FIG. 2. The particular construction of strip 27 and its arrangement in the switch cavity for adjusting the biasing force transmitted to the actuator by toggle spring 103, comprises the invention of Edward O. Andersen, and this construction and arrangement are described and claimed in his copending application Serial No. 78,922 filed concurrently herewith and assigned to the same assignee as the present invention. As shown in FIG. 6, strip 27 is elongated, and at its upper end, it has an enlarged rectangular section 109, with a rectangular slot 111 formed therein. To attach strip 27 to the support, the end of the strip near which slot 111 is formed is extended outwardly, perpendicularly away from, and then back parallel to the principal surface of the strip to provide a generally hooked-shaped fold 113. Fold 113 is wrapped around rib 47 of the support, as shown in FIG. 2, before the assembly of the switch parts within the housing. Bottom end 115, with a tool aperture therein, is extended out of the housing over the flat surface 9a of nut 9 and is pulled to vary the position of pivot edge 105 longitudinally and downwardly. This movement of pivot edge 105 provides the desired compression for spring 103. The bottom of the strip is then welded between the right side 30 of nut 9 and the adjacent bottom end 11 of the casing (FIG. 2) to set the spring biasing force at the desired temperature differential for the switch. Rectangular slot 111 provides clearance for the movement of both of the free ends of the toggle spring 103. Intermediate the 35 ends of the strip 27, an outwardly raised surface 117 is projected toward the wall of the casing to help position the strip 27 within the casing and guide the longitudinal movement of the strip. It will thus be seen that the structure of strip 27 allows convenient adjustment of the 40 biasing force imparted to actuator 55 by toggle spring 103 after the assemblage of the switch parts within cavity 37.

Turning now to an important aspect of my invention, which is the provision in my improved switch of an efficient and accurate means for operating the actuator and contacts thereof by two thermally responsive members in the lower portion of switch cavity 37, I have positioned a force transmission lever 119. Considering first the structure of lever 119, as shown in FIG. 2, it includes a force receiving section 121, an elongated force transmission section 123 which extends perpendicularly upwardly from the left side of section 121, and an actuating section 125 which extends angularly from the upper end of section 123 toward the upper end of the recess formed by embossment 69 in the actuator 55. The outer side of force receiving section 121, as best illustrated in FIG. 8, has a V-shaped knife edge 127 projecting outwardly therefrom. This edge 127 is accurately formed so that it is perpendicular to the longitudinal center line of lever 119 (as may be seen in FIG. 3). On the opposite or inner side of force receiving section 121, and spaced between edge 127 and the adjacent right end of the lever (FIG. 2), a shallow V-shaped groove 129 is formed. The innermost extremity of this groove is accurately parallel to the knife edge 127 and also perpendicular to the longitudinal center line of the lever 119 (viewing FIG. 3). Lever 119 is assembled within switch cavity 37 with a right-angled shim 131 overlying the adjacent outer surfaces of force receiving section 121 and section 123. The inner end of adjustment screw 29 has a frusto-conical shape and it engages the outer side of leg 132 of the shim. The inner side of the shim leg 132 is sharply engaged by knife edge 127 of force receiving section 121 to imbed a knife edged indentation therein. The engagement of knife edge 127 with shim leg 132 provides an accurate 60 pivotal relationship between the housing of the switch 65 and the actuator 55.

and lever 119 which is precisely preserved during the rotation of screw 29 by the engagement of the legs of the shim with the adjacent outer surfaces of sections 121 and 123.

The transverse knife edge 51 of support 35 pivotally engages the shallow groove 129. Support 35 runs in compression between annular flange 17 at the upper end of cavity 37 and groove 129 of lever section 121. It will thus be seen that force receiving section 121 of lever 119 is in compressive engagement with the switch housing by means of screw 29, shim 131, and the V-shaped knife edge 127, and it is also in compressive engagement with the support 35 by means of knife edge 51 and groove 129. The offset points 127 and 129 of the lever thus receive compressive forces from the housing and support, respectively. Each of these compressive forces urges the free end of actuating section 125 of the lever to rotate in a clockwise direction of rotation, as shown in FIG. 2, about the pivot which is compressed by the other force. For example, the compressive arrangement of support 35 within the switch cavity 37 imparts a compressive force to groove 129 of the lever. This compressive force urges the free end of actuating section 125 to rotate in a clockwise direction of rotation about knife edge 127. The compressive force imparted to knife edge 127 by screw 29 through the shim 131 urges the free end of actuating section 125 of the lever to rotate in a clockwise direction about pivot point 129. By arranging the pivotal engagement of the housing and support with lever 119 in this manner, precise and very efficient thermally responsive operation of the actuator is thereby achieved. A thermally responsive elongation of approximately only a few ten thousandths of an inch will efficiently actuate the switch contacts by means of a very high motion amplification.

Turning now to a detailed description of the operation of my improved thermally responsive switch 1, as shown in FIG. 2, movable contact button 97 is in its normally closed position, in engagement with fixed contact button 25. With the contacts of the switch in their normally closed position, the compressive forces imparted to lever 119 at pivots 127 and 129 by the housing and the support are of sufficient magnitude to hold actuator 55 in its closed position against the biasing force of toggle spring 103. With the switch contacts in this position, a major electric current path is provided through the switch from the cylindrically-shaped terminal 15 to the fixed contact terminal 19, through the support 35, the actuator 55, the movable contact strip 75, and the fixed contact button 25. The other conductive parts of the switch, such as the casing and lever, form parallel paths to a portion of the major path, but whatever path is considered, the contacts 97 and 25 will open it when they are separated.

Let us suppose that my improved switch 1 is connected to the control circuit of an apparatus, such as a hermetically sealed motor and supported at upper end 7 of casing 3. The housing of the switch is electrically insulated from its external supporting environment by the aforementioned sleeve 13. When a relatively high rate of ambient temperature occurs, the tubular casing 3 senses this rapid temperature variation considerably faster than the support 35, due to the shielding effect the housing has upon the support. The thermal expansion or contraction of the support 35 always lags that of the tubular member 3 for an increase or decrease in temperature.

With a relatively high rate of increase in ambient temperature, the bottom end 11 of the tubular casing 3 expands longitudinally downwardly a few ten thousandths of an inch from where it is shown in FIG. 2. Nut 9 and screw 29 also move downwardly with casing 3, since they are attached thereto, and the compressive force imparted to knife edge 127 of lever 119 via shim 131 is thereby rapidly reduced. With a rapid reduction in

compressive force at knife edge 127, actuating section 125 of lever 119 is ultimately (i.e., at the value of the predetermined ultimate trip temperature) allowed to move in a counterclockwise direction of rotation (viewing FIG. 2) by the counterclockwise biasing force exerted thereupon by the spring biased actuator 55. This motion causes actuator 55 to move in a counterclockwise direction of rotation about its pivots. As best shown by a comparison of FIG. 2 and FIG. 7, the biasing force of toggle spring 103 moves the free end 95 of the actuator away from inner side 93 of the movable contact extension toward outer side 91 thereof. As the free end of the actuator begins to move away from side 93 toward side 91, the compressive force applied by spring 101 to the movable contact strip urges the movable contact button to rotate in a clockwise direction. Spring 101 thus retains the contacts in engagement until the free end 95 of the actuator has traveled the wiper distance (i.e., the approximate distance between the inner surfaces of sides 91 and 93 minus the thickness of the actuator at its free end 95). The free end 95 of the actuator then engages side 91 of the movable contact strip and thereby pivots the movable contact button 97 out of engagement with the fixed contact button 25 (FIG. 7). This is the open contacts position for the switch.

After the switch contacts have been opened, when the tubular member 3 is cooled, it contracts and thereby diminishes in length. With the occurrence of this temperature condition, lever 119 eventually receives a sufficient compressive force at pivot 127 from the switch housing to overcome the spring biased actuator and reclose the contacts.

Supposing now that my improved switch 1 is exposed to a relatively low rate of increase in temperature, when this ambient condition occurs, the tubular casing 3 and support 35 each expand longitudinally in the same direction, downwardly as shown in FIG. 2, or away from the contact end of the housing. The containment of support 35 by the switch housing has less effect upon transfer of heat to the support for this condition and support 35 receives a significant effect from the thermal variation. Tubular casing 3 thus expands longitudinally a few ten thousandths of an inch, with support 35 expanding longitudinally in the same direction, but to a lesser degree. The compressive force exerted upon knife edge 127 of the lever by screw 29 is then reduced by the thermal expansion of casing 3, but at the same time, the compressive force urged upon pivot groove 129 of the lever by support 35 is gradually increased by the thermal expansion of the support. It will thus be seen that the thermal expansion of support 35 partially compensates for the thermal expansion of tubular casing 3 when the rate of rise in temperature is low enough to allow significant transfer of heat into cavity 37 of the casing. Since the thermally responsive compressive force urged upon lever 119 by support 35 increases in response to temperature rise and partially compensates for the diminishing of the compressive force exerted upon the lever by the housing when there is a relatively slow temperature rise in lieu of a relatively rapid temperature rise, it is necessary for the ambient temperature to reach a higher predetermined value before the contacts of the switch will open. When this higher predetermined temperature value has been reached, actuator 55 of the switch will open the contacts in the same manner as previously described for the relatively high rate of temperature variation.

It will thus be seen that I have provided a new and improved thermally responsive switch which provides compensation for rate of temperature rise. This switch provides an efficient and very accurate motion amplification system for operating a pair of switch contacts by thermally responsive compressive forces from a tubular casing and an inner support. By mounting the force transmission lever in precise pivotal engagement with

the support and the tubular member, an inexpensive and readily assembled means for transmitting the actuating force from the thermally responsive members to the contact actuator has been thereby achieved. My switch also incorporates a very effective means for snapping the switch contacts between their open and closed positions.

FIG. 9 illustrates, as a modified form of my invention, a thermally responsive switch 140. For switch 140, the same reference numerals have been employed to indicate switch parts that have heretofore been described for switch 1. Parts which have a modified structure in comparison to the structure of their correlative parts in switch 1 but perform the same basic functions in the switch 140 are identified by the same reference numeral with the letter "a" suffixed thereto.

To eliminate some of the manufacturing tolerances which would occur in making my improved switch, support 35a has an upper end rib 142 (as shown in FIG. 9) with tab portion 141 formed thereon. Tab portion 141 extends angularly downwardly and away from the bottom side of rib 142 toward the adjacent inner wall of casing 3. The free end of tab portion 141 abuts the casing wall to force the upper end of support 35a laterally toward the left side of the casing and thereby reduce the building up of tolerances during the manufacturing operation for the switch 140. To facilitate clearance for the right side of fixed contact button 25 (FIG. 9), when the upper end of support 35a is positioned in the cavity of switch 140 by tab portion 141, aperture 143 is formed directly to the right of contact button 25.

In order to hermetically seal the bottom end of switch 140, it will be noted that nut 144 therof is smaller than nut 9 of switch 1 and is fitted inside of casing 3 near its bottom. Nut 144 has the same D-shaped configuration as nut 9, but the cylindrical peripheral portion thereof is smooth. A special flat protuberance 147 is formed on the flat right side of nut 144. Nut 144 is welded to the inner wall of the casing 3 at 145. Protuberance 147 extends longitudinally in a plane parallel to the axis of screw 29, and it serves as a supporting projection for receiving the weld of flexible strip 27a after the temperature differential has been properly set. Free end 149 of flexible strip 27a is then looped transversely within the bottom of cavity 37 outwardly of screw 29. After screw 29 is properly adjusted to calibrate the compressive forces exerted upon lever 119, it is welded to nut 144 at 146. Cup-shaped cap 151 is then pressed into its position, as shown in FIG. 9. Cap 151 is flush with the edge of the tube and the smooth surface of its annular rim 153 engages the inner wall of the casing near its bottom. The cap 151 is then welded to the casing, preferably by the heli-arc method, to hermetically seal the switch 140.

Operationally, the modified form of my invention is identical to the arrangement of switch 1 which has been previously described.

The simplicity of my improved switch permits the dimensions to be small compared to other prior art devices affording snap action of the switch contacts, and provides a structure which is readily hermetically sealable. For example, in a thermally responsive switch constructed in accordance with this invention for protecting electric motors of from 1 to 100 horsepower, the device has an over-all length of 3 inches, and a diametrical width of approximately .276 inch.

While in accordance with the patent statutes, I have described what at present are considered to be the preferred embodiments of my invention, it will be obvious to those skilled in the art that various changes and modifications may be made therein without departing from the invention, and I, therefore, aim in the following claims to cover all such equivalent variations as fall within the true spirit and scope of the invention.

What I claim as new and desire to secure by Letters Patent of the United States is:

1. A thermally responsive switch comprising an elongated housing, an elongated support disposed longitudinally within and substantially contained by said housing, said housing and said support each being expandable and contractible longitudinally in response to temperature variations and at respectively different rates with the rate of response of the support lagging that of the housing, lever means disposed within said housing and operable between first and second positions, switch contact means disposed within said housing and operable by said lever means, fixed contact means engaged by said switch contact means when said lever means is in said second position, and resilient means continuously biasing said lever means toward the first position, said lever means including a force receiving section disposed transversely within said housing, one side of said section engaging said housing at a first pivot, the other side of said section engaging said support at a second pivot spaced from said first pivot, said housing and support being arranged to exert offset and oppositely directed thermally responsive forces upon said lever means at said first and second pivots respectively to normally urge said lever means into the second position against the biasing force of said resilient means, the movement of said pivot points upon predetermined temperature conditions being arranged to allow said resilient means to move said lever to said first position, and said resilient means applying an increasing force as said lever means moves from said second position to said first position, thereby to produce a positive temperature differential between said positions of said lever.

2. A thermally responsive switch comprising an elongated housing, an elongated support disposed longitudinally within and substantially contained by said housing, said housing and said support each being expandable and contractible longitudinally in response to temperature variations with the rate of response of the support lagging that of the housing, lever means disposed within said housing and operable between first and second positions, switch contact means disposed within said housing and operable by said lever means, fixed contact means engaged by said switch contact means when said lever means is in said second position, and snap acting resilient means continuously biasing said lever means toward the first position, said lever means including a force receiving section disposed transversely within said housing, one side of said section engaging said housing at a first pivot, the other side of said section engaging said support at a second pivot spaced transversely from said first pivot, said housing and support being arranged to exert offset and oppositely directed thermally responsive forces upon said lever means at said first and second pivots respectively to tend to move the pivots and normally urge said lever means into the second position against the biasing force of said resilient means, the movement of said pivot points upon predetermined temperature conditions being arranged to allow said resilient means to move said lever to said first position, and said resilient means applying an increasing force as said lever means moves from said second position to said first position, thereby to produce a positive temperature differential between said positions of said lever.

3. A thermally responsive switch comprising an elongated tube and an elongated support disposed longitudinally within said tube, said tube and said support being expandable and contractible longitudinally in response to temperature variations with the rate of response of the support lagging that of the tube, a lever member disposed within said tube and operable between first and second positions, an actuator pivotally mounted upon said support and continuously engaged by said lever, switch contact means disposed within said tube and operable by said actuator, and snap acting resilient means continuously

biasing said actuator to urge said lever toward the first position, said lever member including a force receiving section disposed transversely within said tube, one side of said section engaging said tube at a first pivot, the other side of said section engaging said support at a second pivot spaced transversely from said first pivot, said tube and support being arranged to exert offset and oppositely directed thermally responsive forces upon said lever member at said first and second pivots respectively to tend to move the pivots and normally urge the lever member into the second position against the biasing force of said resilient means, the movement of said pivot points upon predetermined temperature conditions being arranged to allow said resilient means to move said lever to said first position.

4. A thermally responsive switch comprising an elongated tube and an elongated support disposed longitudinally within said tube, said tube and said support being expansible and contractible longitudinally in response to temperature variations with the rate of response of the support lagging that of the tube, a lever member disposed within said tube and operable between first and second positions, an actuator pivotally mounted upon said support and continuously engaged by said lever, switch contact means disposed within said tube and operable by said actuator, and snap acting resilient means continuously biasing said actuator to urge said lever toward the first position, said lever member including a force receiving section disposed transversely within said tube, one side of said section compressively engaging an inner end of the tube at a first pivot, the other side of said section compressively engaging one end of the support at a second pivot spaced transversely from said first pivot, said tube and support being arranged to exert offset and oppositely directed thermally responsive forces upon said lever member at said first and second pivots respectively to tend to move the pivots longitudinally in opposite directions and normally urge the lever member into the second position against the biasing force of said resilient means, the movement of said pivot points upon predetermined temperature conditions being arranged to allow said resilient means to move said lever to said first position.

5. A thermally responsive switch comprising an elongated tube and an elongated support disposed longitudinally within said tube, said tube and said support being expansible and contractible longitudinally in response to temperature variations with the rate of response of the support lagging that of the tube, a lever member disposed within said tube and operable between first and second positions, an actuator pivotally mounted upon said support and continuously engaged by said lever, switch contact means disposed within said tube and operable by said actuator, said switch contact means including a movable contact pivotally mounted upon said actuator and carried thereby, and snap acting resilient means continuously biasing said actuator to urge said lever toward the first position, said lever member including a force receiving section disposed transversely within said tube, one side of said section engaging said tube at a first pivot, the other side of said section engaging said support at a second pivot spaced transversely from said first pivot, said tube and support being arranged to exert offset and oppositely directed thermally responsive forces upon said lever member at said first and second pivots respectively to tend to move the pivots and normally urge the lever member into the second position against the biasing force of said resilient means, the movement of said pivot points upon predetermined temperature conditions being arranged to allow said resilient means to move said lever to said first position.

6. The switch of claim 5 including a compression spring extending between the actuator and the movable contact to normally bias the movable contact toward a fixed contact and provide a wiping action for the switch contact means.

7. The switch of claim 5 including a sleeve of electrical and thermally conductive insulating material substantially surrounding the tube, said sleeve being thermally shrinkable and substantially contiguous to said tube, thereby to electrically insulate the switch from an external supporting environment while providing little resistance to transfer of heat to said tube.

8. A thermally responsive switch comprising an elongated tube and an elongated support disposed longitudinally within said tube, said tube and said support being expansible and contractible longitudinally in response to temperature variations with the rate of response of the support lagging that of the tube, an adjusting means mounted in said tube, a lever member disposed within said tube and operable between first and second positions, an actuator pivotally mounted upon said support and continuously engaged by said lever member, switch contact means disposed within said tube and operable by said actuator, said switch contact means including a movable contact pivotally mounted upon said actuator and carried thereby, said lever member, actuator, and movable contact constituting a balanced lever system in said switch, and snap acting resilient means continuously biasing said actuator to urge said lever toward the first position, said lever member including a force receiving section disposed transversely within said tube, one side of said section compressively engaging the adjusting means of said tube at a first pivot, the other side of said section compressively engaging said support at a second pivot spaced transversely from said first pivot, said adjusting means and support being arranged to exert offset and oppositely directed thermally responsive forces upon said lever member at said first and second pivots respectively to tend to move the pivots and normally urge the lever member into the second position against the biasing force of said resilient means, the movement of said pivot points upon predetermined temperature conditions being arranged to allow said resilient means to move said lever to said first position, said adjusting means being linearly movable to vary the compressive forces imparted to said lever by said tube and said support thereby to calibrate said switch.

9. A hermetically sealed thermally responsive switch comprising an elongated tube and an elongated support disposed longitudinally within said tube, said tube and said support being expansible and contractible longitudinally in response to temperature variations with the rate of response of the support lagging that of the tube, said tube having a pair of oppositely disposed open ends, closure means for hermetically sealing each of the open ends of said tube, a lever member disposed within said tube and operable between first and second positions, an actuator pivotally mounted upon said support and continuously engaged by said lever, switch contact means disposed within said tube and operable by said actuator, snap acting resilient means continuously biasing said actuator to urge said lever toward the first position, said lever member including a force receiving section disposed transversely within said tube, one side of said section engaging said tube at a first pivot, the other side of said section engaging said support at a second pivot spaced transversely from said first pivot, said tube and support being arranged to exert offset and oppositely directed thermally responsive forces upon said lever member at said first and second pivots respectively to tend to move the pivots and normally urge the lever member into the second position against the biasing force of said resilient means, the movement of said pivot points upon predetermined temperature conditions being arranged to allow said resilient means to move said lever to said first position.

10. A thermally responsive switch comprising an elongated tube and an elongated support disposed longitudinally within said tube, said tube and said support being expansible and contractible longitudinally in response to temperature variations with the rate of response

of the support lagging that of the tube, a lever member disposed within said tube and operable between first and second positions, an actuator pivotally mounted upon said support and continuously engaged by said lever, switch contact means disposed within said tube near one end thereof and operable by said actuator, a snap acting U-shaped toggle spring continuously biasing said actuator to urge said lever member toward the first position, said lever member including a force receiving section disposed transversely within said tube near the other end thereof between said other end and an adjacent end of the support, one side of said section compressively engaging said other end of the tube at a first pivot, the other side of said section compressively engaging said end of the support at a second pivot spaced transversely from said first pivot, said tube and support being arranged to exert offset and oppositely directed thermally responsive forces upon said lever member at said first and second pivots respectively to tend to move the pivots longitudinally in opposite directions and normally urge the lever member into the second position against the biasing force of said toggle spring, the movement of said pivot points upon predetermined temperature conditions being arranged to allow said resilient means to move said lever to said first position.

11. A thermally responsive switch comprising an elongated tube and an elongated support disposed longitudinally within said tube, said tube and said support being expandible and contractible longitudinally in response to temperature variations with the rate of response of the support lagging that of the tube, a lever member disposed within said tube and operable between first and second positions, an actuator pivotally mounted upon said support and continuously engaged by said lever, switch contact means disposed within said tube near one end thereof and operable by said actuator, a snap acting U-shaped toggle spring continuously biasing said actuator to urge said lever member toward the first position, one side of said toggle spring being in continuous engagement with said actuator and the other side of said spring being in pivotal engagement with a tensioned supporting strip, said lever member including a force receiving section disposed transversely within said tube near the other end thereof between said other end and an adjacent end of the support, one side of said section compressively engaging said other end of the tube at a first pivot, the other side of said section compressively engaging said end of the support at a second pivot spaced transversely from said first pivot, said tube and support being arranged to exert offset and oppositely directed thermally responsive forces upon said lever member at

said first and second pivots respectively to tend to move the pivots longitudinally in opposite directions and normally urge the lever member into the second position against the biasing force of said resilient means, the movement of said pivot points upon predetermined temperature conditions being arranged to allow said resilient means to move said lever to said first position.

12. A thermally responsive switch comprising an elongated tube and an elongated support disposed longitudinally within said tube, said tube and said support being expandible and contractible longitudinally in response to temperature variations with the rate of response of the support lagging that of the tube, a lever member disposed within said tube and operable between first and second positions, an actuator pivotally mounted upon said support and continuously engaged by said lever, switch contact means disposed within said tube and operable between open and closed positions by said actuator, said switch contact means including a movable contact pivotally mounted upon said actuator and carried thereby, means for limiting the free travel of said movable contact to assure that the contacts will remain in their closed position under normal external vibrations, and snap acting resilient means continuously biasing said actuator to urge said lever toward the first position, said lever member including a force receiving section disposed transversely within said tube, one side of said section engaging said tube at a first pivot, the other side of said section engaging said support at a second pivot spaced transversely from said first pivot, said tube and support being arranged to exert offset and oppositely directed thermally responsive forces upon said lever member at said first and second pivots respectively to tend to move the pivots and normally urge the lever member into the second position against the biasing force of said resilient means, the movement of said pivot points upon predetermined temperature conditions being arranged to allow said resilient means to move said lever to said first position.
